UNITED STATES PATENT OFFICE.

JAMES M. HOPKINS, OF CHICAGO, ILLINOIS.

RAILWAY-CAR TRUCK.

No. 811,062.

Specification of Letters Patent.

Patented Jan. 30, 1906.

Application filed June 5, 1905. Serial No. 263,708.

To all whom it may concern:

Be it known that I, JAMES M. HOPKINS, a citizen of the United States, residing at Chicago, county of Cook, and State of Illinois, 5 have invented certain new and useful Improvements in Railway-Car Trucks, of which I do declare the following to be a full, clear, and exact description, reference being had to the accompanying drawings, forming part of 10 this specification.

The present invention has for its object to provide an improved construction of car-truck; and the invention consists in the features of novelty hereinafter described, illustrated in the accompanying drawings, and particularly pointed out in the claims at the end of this specification.

Figure 1 is a view in vertical section on line 1 1 of Fig. 2 through the bolster, spring-plank, side frames, &c., of a car-truck embodying my invention. Fig. 2 is a view, partially in plan and partially in horizontal section, through my improved truck. Fig. 3 is a view in side elevation, showing the central 25 portion of one of the side frames of the truck and the parts in position for use therein.

The side frames A and A' of the truck may be formed of steel in any approved manner, and each of these side frames is provided 30 with a central opening a, the walls of these side openings a serving to retain in position the parts within the openings. Through the lower portion of the openings a in the side frames A and A' extend the ends of the spring-plank or transom B. As shown, the spring-plank B is formed of a channel-bar of steel or iron, and upon the end portions of the spring-plank B rest the spring-supporting plates C, whereon the groups of springs D are suspended. 35 As shown, these spring-supporting plates C are formed with slightly-raised portions c, through which pass the retaining-bolts E, that extend through the springs D, the upper ends of these bolts E passing 40 through retaining-plates C', whereon rest the spring-caps F. Each of the spring-caps F is formed with outwardly-projecting flanges or ribs f, that engage the walls or pillars a² at the sides of the square frame-openings a, these 45 ribs or flanges f serving to interlock the spring-caps F with the frames A and A'.

Upon each of the spring-caps F rests one 50 end of the bolster G, the ends of this bolster projecting through the upper portions of the openings a in the side frames A and A'. The

bolster G may be of steel, and preferably for greater strength the bolster is provided with a central rib g, extending from end to end thereof.

In order to securely interlock the bolster G 60 with the spring-caps F, each end of the bolster G is provided with a downwardly-projecting flange g', that engages the subjacent spring-cap.

When the parts are to be assembled, the 65 spring-plank B will be set in position, as shown, after which the ends of the bolster G will be placed within the upper portion of the openings a of the side frames. Then the spring-caps F will be placed diagonally with- 70 in the square openings a of the side frames, with the ribs or flanges f in position to engage the walls or pillars a² of the side frames, and the spring-caps F will then be brought to horizontal position against the under sides of the 75 ends of the bolster. As the spring-caps F are thus brought to horizontal position the ribs or flanges f will lie upon opposite sides of the walls or pillars a², and thus guard the spring-caps F against movement. The springs 80 D will then be compressed and with the plates C will be placed in position for use, as shown in the drawings. Inasmuch as the spring-caps F are thus interlocked with the side frames A and A' and inasmuch as the 85 flanged ends of the transom G engage the spring-caps F, the several parts will be securely held against accidental displacement, while allowing sufficient yield to compensate for the strains and shocks to which the 90 trucks are inevitably subjected.

It will thus be seen that with my improved truck the parts can be simply and cheaply made and readily assembled and when in position for use will provide a most effective and 95 durable construction. Moreover, when repairs are to be made or parts replaced the parts of the truck may be easily removed for such purpose.

It is manifest that the precise details of 100 construction above set out may be varied without departing from the spirit of the invention.

Having described my invention, what I 105 claim as new, and desire to secure by Letters Patent, is—

1. A car-truck comprising side frames having openings therein, spring-planks with springs thereon, spring-caps interlocked with said side frames and an integral bolster pro- 110

jecting through the openings of the side frames and having its ends flanged or offset to engage said spring-caps.

2. A car-truck comprising side frames having openings therein, spring-planks with springs thereon, spring-caps interlocked with said side frames and an integral bolster projecting through the openings of the side frames and having its ends provided with 10 downwardly-projecting flanges engaging said spring-caps.

3. A car-truck comprising metal side frames having openings therein, the portions

of said side frames surrounding said openings being formed integral, spring-planks with 15 springs thereon, spring-caps interlocked with said side frames and an integral bolster projecting through the openings of the side frames and having its ends provided with 20 downwardly-projecting flanges engaging said spring-caps.
